(57) **CLAIM**

The ornamental design for a reversible motion detector device as shown and described.

DESCRIPTION

FIG. 1 is a top view of a reversible motion detection device shown in a state of use in the right-hand position mounted on a chair.

FIG. 2 is an enlarged perspective view of a reversible motion detection device shown in a state of use in the right-hand position mounted on a chair.

FIG. 3 is a front view of a reversible motion detection device shown in a state of use in the right-hand position mounted on a chair.

FIG. 4 is a back view of a reversible motion detection device shown in a state of use in the right-hand position mounted on a chair.

FIG. 5 is a left view of a reversible motion detection device shown in a state of use in the right-hand position mounted on a chair.

FIG. 6 is a right view of a reversible motion detection device shown in a state of use in the right-hand position mounted on a chair.

FIG. 7 is a top view of a reversible motion detection device shown in a state of use in the right-hand position mounted on a chair.

FIG. 8 is a bottom view of a reversible motion detection device shown in a state of use in the right-hand position mounted on a chair.

FIG. 9 is a top view of a reversible motion detection device shown in a state of use in the left-hand position mounted on a chair.

FIG. 10 is an enlarged perspective view of a reversible motion detection device shown in a state of use in the left-hand position mounted on a chair.

FIG. 11 is a front view of a reversible motion detection device shown in a state of use in the left-hand position mounted on a chair.

FIG. 12 is a back view of a reversible motion detection device shown in a state of use in the left-hand position mounted on a chair.

FIG. 13 is a left view of a reversible motion detection device shown in a state of use in the left-hand position mounted on a chair.

FIG. 14 is a right view of a reversible motion detection device shown in a state of use in the left-hand position mounted on a chair.

FIG. 15 is a top view of a reversible motion detection device shown in a state of use in the left-hand position mounted on a chair.

(Continued)

FIG. 16 is a bottom view of a reversible motion detection device shown in a state of use in the left-hand position mounted on a chair.

FIG. 17 is a top perspective view of the reversible motion detector device.

FIG. 18 is a rear view of the reversible motion detector device.

FIG. 19 is a front view of the reversible motion detector device.

FIG. 20 is a left view of the reversible motion detector device.

FIG. 21 is a right view of the reversible motion detector device; and,

FIG. 22 is a top view of the reversible motion detector device in a reversed configuration.

In the drawings, the dot-dash broken lines depict the boundaries of the enlarged views in FIGS. 2 and 10 and form no part of the claimed design.

In the drawings, the broken lines depict portions of the reversible motion detection device that form no part of the claimed design.
